METHOD OF MAKING SLIDE FASTENERS

Henry W. Brownson, Birmingham, England,
assignor to Hookless Fastener Company, a
corporation of Pennsylvania

Original application October 15, 1932, Serial No.
637,984, now Patent No. 1,920,138, dated July
25, 1933. Divided and this application July 21,
1933, Serial No. 681,529. In Great Britain
October 17, 1931.

2 Claims. (Cl. 18—59)

This invention relates to separable interlocking fasteners in which two rows of fastener members are attached to a pair of tapes and so constructed that the elements of one row interlock with those 5 of the other row. The fastener members may assume various forms, the form used in illustrating this invention being that of a well known slide fastener in which the two rows of fastener elements are interlocking and separated by a 10 slider.

This application is a division of the application, Ser. No. 637,984, filed October 15, 1932, jointly with George H. C. Corner, now Patent No. 1,920,138.

15 It is among the objects of this invention to provide a strong and improved bond between non-metallic fastener members and their supporting strips or tapes. More specifically it is one of my objects to provide a fastener in which 20 there is an integral bond between the fastener members and the supporting strips or tapes.

One of the features of the invention consists in forming an intimate joint between each individual interlocking element and a supporting strip, for example, a homogeneous, autogenous, 25 or physico-chemical bond between the interlocking element and material constituting or included in the strip.

Other objects and advantages of the invention 30 will be apparent from the accompanying description and drawing, in which:

Fig. 1 is a perspective view of a complete fastener stringer embodying the invention.

Fig. 2 is a cross-section of a tape at one stage 35 of the manufacture of a fastener in accordance with one embodiment of my invention, the proportions of some elements being exaggerated for clearness, and

Fig. 3 is an enlarged perspective view of a tape 40 after being prepared, as indicated in Fig. 2, for the attachment of the interlocking elements.

In Fig. 1, 10 represents a flexible supporting member, preferably in the form of a fabric tape, to the edge of which are secured in uniformly 45 spaced relation a number of interlocking elements, exemplified as including an interlocking head portion 12 projecting from the edge of the tape and a supporting base portion bifurcated to provide two legs 14 which straddle the tape 50 and are secured to it.

In accordance with the present invention the interlocking elements are formed of non-metallic material, examples of which are cellulose ester or ether materials, such as pyroxylin or nitro-cellulose; synthetic resins, such as resinous poly-

merized unsaturated organic compounds, phenol-aldehyde resins, urea- or thiourea-aldehyde resins, polyhydric-alcohol-polybasic acid resins; and compressed and/or impregnated fiber.

For the sake of illustration, we may consider 5 that the interlocking elements are formed of cellulose benzyl ether molding powder. A thin strip of plasticized cellulose benzyl ether which has been softened by heat or by soaking in a solvent, is applied to one or both faces of a fabric strip along one edge. In Fig. 2 the fabric strip 10 is placed between the bonding strips 16 of softened cellulose benzyl ether and pressed between two rollers 18. This operation rolls the strips 18 into the interstices of the fabric and 10 forms an intimate attachment between the two, resulting in a perfectly flexible fabric base 15 impregnated with the cellulose benzyl ether to form an adhesive or bonding edge, as shown in Fig. 3. The completely formed interlocking elements in 20 this instance made of cellulose benzyl ether, are then placed along the tape as shown in Fig. 1, in the desired closely and uniformly spaced relation and attached to the tape. Conveniently the interlocking elements may be applied while the 25 strips 18 are still soft from the rolling operation but preferably the strips 16 and the jaws 14 are softened for this step in the process. When the solvent evaporates, the stickiness of the material 30 disappears and the interlocking elements are 30 integrally united to the strips 16 which previously have been pressed into the interstices of the fabric tape. The supporting tape thus contains an 35 intimately and firmly attached root or support, intermingled with the fibers of the fabric, which support has become integral with the material of the interlocking elements. Likewise the interlocking elements are homogeneously united to the bearing elements 16. However, the strips 16 40 do not impair the flexibility of the tape.

The term "bonding material" as used herein and in the appended claims means a material in the plastics class which under ordinary conditions of temperature and pressure is hard and which is capable of being softened by the action 45 of heat or solvent. The term "impregnated" as used in conjunction with "bonding material" means forced into the interstices of the fabric or equivalent porous support by the action of pressure while the material is in a soft or semi-soft 50 condition and is intended to distinguish from the mere common application of liquid or semi-liquid cement.

The interlocking elements may also be applied 55 first and softened after application. This soft-

tenting may be accomplished by heat, or the tape may be saturated either with a suitable solvent alone, or with a solution of the material of which the elements are formed. This acts to soften the inner faces of the applied prongs.

5 While I have shown and described in this application one embodiment which my invention may assume in practice, it will be understood that this embodiment is merely for the purpose 10 of illustration and description and that various other forms may be devised within the scope of my invention as defined in the following claims.

What I claim as my invention is:

15 1. The method of making separable interlocking fasteners of the type having fastener elements uniformly spaced along the edge of a fabric support, which consists in applying bonding material continuously along the supporting edge under sufficient pressure to cause said material to 20 impregnate the fabric, arranging a series of fastener elements at uniformly spaced intervals on

said bonding material, and uniting the same thereto by temporarily softening the material of the contacting surfaces sufficiently to cause them to adhere together.

2. The method of making separable interlocking fasteners of the type having fastener elements secured to a fabric support at uniformly spaced intervals, which consists in applying thin strips of bonding material to the supporting edge while in a semi-plastic condition and with sufficient pressure to cause said bonding material to impregnate the fabric, said bonding material being soluble, and arranging fastener elements made of a material soluble in the same solvent as said bonding strips at uniformly spaced intervals along the supporting edge, and thereafter softening the surfaces of said bonding material and fastener elements by solvent sufficiently to cause them to adhere together.

HENRY W. BROWNSDON.
